UNITED STATES PATENT OFFICE.

BERNHARD DREYFUS, OF NEW YORK, N. Y.

DESIGN FOR A CURTAIN-BAND.

SPECIFICATION forming part of Design No. 12,788, dated February 21, 1882.

Application filed January 24, 1882. Term of patent 14 years.

To all whom it may concern:

Be it known that I, BERNHARD DREYFUS, of the city, county, and State of New York, have invented a new and Improved Design 5 for Curtain-Bands, of which the following is a full, clear, and exact description.

Reference is to be had to the accompanying drawings, forming part of this specification, in which similar letters of reference indicate 10 corresponding parts in both figures.

Figure 1 is a face view of my newly-designed curtain-band; and Fig. 2 is a face view of a part of the same, enlarged to show the details more clearly.

15 My invention relates to bands for holding curtains, draperies, and masks.

A represents the band, which is formed of intersecting strands B, tufts C, buttons D, and border-cords E. The strands B intersect in 20 three rows of points, which rows are wider apart in the middle part of the band, and gradually approach each other toward the ends of the said band. To the strands B at the points of intersection forming the side rows are tied the 25 tufts C. Along the center line points of strand intersections of the band are secured molds or buttons D, the points of attachment depending upon the size of the molds D used, and

may be varied without departing from my design. In the drawings the molds D are represented as being attached at a point of intersection, and midway between the next two points, and so on in regular order. At the edges of the band the strands B are tied to the border-cords E, and at the ends of the 35 band are formed cord-loops F.

Materials of different colors may be used to produce pleasing ornamental effects and to cause the bands to harmonize with the colors of the curtains or draperies to which they are 40 applied.

The bands are made of various shapes and sizes; but the form shown in Fig. 1 is preferred.

Having thus described my invention, I claim 45 as new and desire to secure by Letters Patent—

The design for curtain-bands herein shown and described, the same consisting of the intersecting strands B, having two rows of tufts, C, a central row of molds or buttons, D, and a 50 border-cord, E, attached to them, substantially as herein shown and described.

BERNHARD DREYFUS.
